UNITED STATES PATENT OFFICE.

HERBERT L. STULL, OF STROUDSBURG, PENNSYLVANIA.

SNOW-MELTING ATTACHMENT FOR LOCOMOTIVES.

1,219,185.

Specification of Letters Patent. Patented Mar. 13, 1917.

Application filed January 24, 1917. Serial No. 144,225.

To all whom it may concern:

Be it known that I, HERBERT L. STULL, a citizen of the United States, residing at Stroudsburg, in the county of Monroe and State of Pennsylvania, have invented certain new and useful Improvements in Snow-Melting Attachments for Locomotives, of which the following is a specification.

My invention relates to improvements in snow melting attachments for locomotives, the object of the invention being to provide an attachment for locomotives which can be readily placed in position on the cow-catcher, and which operates to direct a large number of steam jets into snow at the desired angle to effectually melt the snow in advance of the wheels of the locomotive.

A further object is to provide an improved rack adapted to be removably secured to a cow-catcher, and support any number of steam pipes having discharge jets for directing the steam at the desired angles to most efficiently melt the snow.

With these and other objects in view the invention consists in certain novel features of construction and combinations and arrangements of parts as will be more fully hereinafter described and pointed out in the claims.

In the accompanying drawings:

Figure 1 is a fragmentary view in side elevation, illustrating my improvements.

Fig. 2 is a plan view of Fig. 1, and

Figs. 3, 4, 5, and 6 are views illustrating details of construction.

1 represents the front end of a locomotive equipped with the ordinary cow-catcher 2. 3 represents my improved rack which consists of two side brackets 4, 4, connected by diagonal braces 5. These brackets 4, 4, each consists of a bar of metal having its intermediate portion vertically disposed as shown at 6, and having its upper end 7 projecting rearwardly and secured by a bolt 8 or other securing device to the upper portion of the cow-catcher.

The lower ends of the brackets are provided with rearwardly projecting arms 9 which are secured by bolts 10 or other securing devices to the lower bar of the cow-catcher, and braces 9^a connect intermediate portions of the brackets with the cow-catcher to strengthen the structure.

The portions 6 of the brackets are parallel to each other, and are provided with supporting hooks 11 receiving horizontal pipes

12. These horizontal pipes 12 have each a longitudinal series of steam discharge nozzles 13, and set-screws 14 are provided in the hooks 11 and jam against the pipes 12 holding them securely in the hooks.

The pipes 12 are preferably made in sections, as shown, T-couplings 15 being utilized to connect the sections, and caps or blocks 16 are provided on the ends of the pipes.

The pipes 12 are arranged in pairs, and as many pairs used as may be desired. The T-couplings of each pair are connected by couplings 17 with a manifold 18, and the latter with the steam supply pipe 19.

It is of course to be understood that where a large number of pairs of pipes 12 are used it may be necessary to use an extra locomotive to furnish the necessary steam supply, and variations may be necessary to accommodate the structure to different conditions.

Various slight changes might therefore be made in the general form and arrangement of parts described without departing from my invention, and hence I do not limit myself to the precise details set forth, but consider myself at liberty to make such changes and alterations as fairly fall within the spirit and scope of the appended claims.

Having fully described my invention what I claim as new and desire to secure by Letters Patent is:

1. An attachment of the character described, comprising a rack adapted to be removably secured to the cow-catcher of a locomotive, and a horizontal steam discharge pipe in the rack and having a series of steam discharge orifices.

2. An attachment of the character described, comprising a rack, consisting of parallel brackets adapted to be removably connected at their ends to a cow-catcher, said brackets having hooks thereon, and horizontal steam pipes supported in the hooks.

3. An attachment of the character described, comprising a rack having hooks thereon, a pair of horizontal steam pipes supported in the racks and having each a longitudinal series of discharge nozzles, intake manifolds connecting the pair of pipes, and means for directing steam into the manifolds.

4. The combination with a cow-catcher, of a rack having side brackets, each bracket having rearwardly projecting ends remov-

ably secured to the cow-catcher, hooks on the brackets, horizontal pipes supported on the hooks and consisting each of a plurality of sections having inlets, flexible hose removably connected to the inlets, and means to supply steam to the hose.

5. An attachment of the character described, comprising a rack consisting of side brackets, braces connecting the side brackets, 10 hooks on the brackets, horizontal pipes in the hooks, set-screws in the hooks engaging the pipes, a plurality of steam inlets in each pipe, a plurality of discharge nozzles in each pipe, a manifold connecting the inlets, and 15 means for directing steam into the manifold.

6. An attachment of the character de-

scribed, comprising a rack consisting of two side brackets having vertical portions adapted to be located in front of a cow-catcher, and having each a vertical series of hooks thereon, a pair of horizontal pipes supported in the hooks and having steam discharge nozzles, an inlet manifold removably connected to both of said pipes, and 25 means for directing steam into the manifold.

In testimony whereof I have signed my name to this specification in the presence of two subscribing witnesses.

HERBERT L. STULL.
